UNITED STATES PATENT OFFICE.

WALTER C. CANTERBURY, OF BECKLEY, WEST VIRGINIA.

MINE DOOR.

Application filed January 12, 1924. Serial No. 685,865.

To all whom it may concern:

Be it known that I, WALTER C. CANTERBURY, a citizen of the United States, residing at Beckley, in the county of Raleigh and State of West Virginia, have invented a new and useful Mine Door, of which the following is a specification.

This invention relates to doors such as used in mines for normally closing passages or corridors, thereby to facilitate ventilation. It has reference more particularly to means for operating the door by the movement of a car toward the gate from either direction.

One of the objects of the invention is to provide a door operating mechanism utilizing an operating rail of novel construction adapted to be depressed by the weight of a car approaching the door, the rail being so shaped as to be held by the wheels of the car in proper relation to the adjacent rail of the track.

Another object is to provide a structure of this character utilizing a single spring whereby all portions of the mechanism, including the door or doors, are held yieldingly in normal positions.

A further object is to provide operating mechanism which permits the use of doors extending straight across the track, there being novel connections between the doors and the operating mechanism whereby the doors can be moved automatically through ninety degrees or more when opened.

Another object is to provide a door operating mechanism especially useful in narrow or restricted passages, the said mechanism being extended between the doors and the sides of the frame in which they are mounted so as not to necessitate lateral excavations to accommodate the mechanism.

A still further object is to provide a mechanism of this character utilizing shock absorbing means for preventing abrupt application of power to the doors tending to injure the doors or the mechanism.

A further object is to provide a door operating mechanism which is simple, durable and compact, will operate efficiently under all conditions, and permits the use of doors of light construction.

With the foregoing and other objects in view which will appear as the description

proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings:

Figure 1 is a plan view of the door operating mechanism, the gates and their supporting frame being shown in horizontal section.

Fig. 2 is a section on line 2—2, Fig. 1.

Fig. 3 is an enlarged section on line 3—3, Fig. 1.

Fig. 4 is a detail view of one of the cushioning connections.

Fig. 5 is a horizontal section through a portion of one of the doors and showing its connection with the operating mechanism.

Fig. 6 is a longitudinal section through the joint of one of the operating rails.

Fig. 7 is a side elevation of the lower end of one of the operating rails.

Fig. 8 is an end elevation of the lower end of one of the operating rails, the bearing therefor and the track rail being shown in section.

Referring to the figures by characters of reference, R designates the track rails extending over the sill 1 of a door frame, the side posts or jambs 2 supporting the top rail or head 3 and being located laterally beyond the sides of the track. Doors 4 and 5 are mounted to swing within the frame about pivotal connections 6 engaging the sill 1 and the head 3, these doors being preferably spaced inwardly from the jambs 2 so as to accommodate portions of the operating mechanism. The doors and their frame are preferably extended straight across the track, said doors, when closed, being disposed in lapped relation, as shown in Fig. 1.

Extending transversely under the rails R at desired distances apart are angle bars 7 to each of which are connected spaced brackets 8 extending laterally from the bars and supporting a shaft 9 that extends under one of the rails and laterally beyond the

track. In Fig. 1 three of these shafts have been shown under one of the rails R at one side of the door. It is to be understood that a similar arrangement of shafts is to be provided under the other rail at the opposite side of the door.

Extending along the inner side of the rail R under which the shafts 9 extend is an operating rail 10. As shown in Fig. 8 this 10 rail includes an angle rail 11 having an up-standing longitudinal flange 12 lying close to the inner side of the rail R. To this angle rail 11 is secured a channeled rail 13 the flanges of which are extended downwardly, 15 the rails 11 and 13 being fastened together by rivets or any other suitable way.

The operating rail 10 is formed preferably of two sections, a short section 14 and a long section 15. The short section has one end 20 tapered as shown at 16 and extending between the rails R of the track. Fitted in the channeled portions 13 of section 14 close to the tapered end is a block 17 the lower end of which is rounded as shown by dotted lines 25 at 18 in Fig. 7. This rounded end bears within a recess 19 formed in a bearing member 20. This member has a plate 21 extending laterally therefrom under the rail R and the rail and plate are held assembled 30 securely in any manner desired. It will be apparent that the connection described allows the rail section 14 to swing relative to the plate 21 and for the purpose of adjusting the operating rail 10 so that it will be supported close to the inner side of the head of rail R, there is provided an adjusting screw 22 in the end wall of recess 19. This 35 screw bears against block 17, as shown in Fig. 8 and by means thereof said block and the operating rail can be minutely adjusted 40 as will be apparent.

Secured in the channeled portions of the meeting ends of sections 14 and 15 are downwardly extending brackets 23 pivotally 45 connected by links 24 or in any other suitable manner. Thus there is provided a movable connection between the two sections of the operating rail.

Extending from one of the shafts 9 is a 50 crank arm 25 connected by a link 26 to one of the brackets 23. Each of the other shafts 9 is also provided with a crank arm 27 connected by a link 28 to a bracket 29 secured in the channeled portion of the rail section 55 15. These crank arms 27 and 25 are located beneath the rail section 15.

Extending upwardly from the shaft 9 nearest the door frame is an elongated lever 30. Shorter levers 31 are extended upwardly 60 from the other shafts 9. Links 32 are pivotally connected to the upper end of the lever 31 on the intermediate shaft 9 and these links are connected by an adjustable rod 33 to lever 30. Another adjustable rod 34 connects said links to a cross head 35 slidably

mounted within a yoke 36 that is pivotally connected to that lever 31 nearest the rail section 14. A spring 37 is arranged within the yoke and upon rod 34, this spring bearing at one end against the cross head 35 and at its other end against the intermediate portion of the yoke. Thus a cushion is provided for absorbing shocks resulting from the abrupt movement of the mechanism.

Secured to the hingedly mounted side of door 4 is an arcuate arm 38 extending laterally beyond the door and away from lever 30. A rod 39 is pivotally connected to this arm and extends between door 4 and the adjacent jamb 2. As shown in Fig. 1 this rod is connected to a cross head 40 slidable in a yoke 41 pivotally connected to lever 30. A spring 42 is arranged on the rod and within the yoke and acts as a cushioning means, the construction and operation being the same as has already been described with reference to Fig. 4. Yoke 41 can be connected adjustably to lever 30 by placing its pivot pin 43 in any one of a longitudinal series of apertures 44 formed in the lever.

As heretofore pointed out there is provided at both sides of the doors the same arrangement of shafts 9, etc., as has already been described. One of the shafts corresponding to a shaft 9 and located at the opposite side of the doors have been disclosed at 45. This shaft is extended under an operating rail 46 similar to the rail 10 but located back of the door 5 instead of the door 4. Shaft 45 has a lever 47 corresponding with levers 25 and 27 and connected to the rail 46. It also has an upstanding lever 48 to which is pivotally connected a yoke 49. This yoke is slidably engaged by a cross head 50 connected by a rod 51 to an arcuate arm 52 secured to the door 5. This arm is attached to the door at its pivoted side and is extended laterally therefrom away from lever 48. A spring 53 is mounted in the yoke 49 and a cushioning structure is thus provided corresponding with that disclosed in Fig. 4.

A shaft 54 is aligned with and coupled to shaft 45 and journaled in suitable supporting means such as shown at 55. This shaft has an elongated lever 56 extended upwardly therefrom and a coiled spring 57 connects the upper ends of the levers 30 and 56 and acts to draw them toward each other. An intermediate lever 58 is fulcrumed on the jamb 2 adjacent levers 30 and 56 and the upper arm of this lever is connected by a rod 59 to lever 56 while the lower arm of the lever 58 is connected by a rod 60 to lever 30.

As spring 57 constantly pulls upon the two levers 30 and 56 it will be obvious that it acts to hold all of the crank arms 25, 27 and 47 yieldingly elevated with the operating rails 10 supported as shown in Figs. 2 and 3. Likewise the doors 4 and 5 are nor-

5 mally pressed together as shown in Fig. 1 so as to close the door opening. When a car traveling along the track approaches the door the wheels at one side thereof will ride 10 on the inclined end section 14 of the operating rail and force it downwardly. Thus arm 25 will rotate its shaft 9 and motion will be transmitted through the levers 31 and rods 34 and 33 to the other shafts 9 and to lever 15 30. The instant these rail sections are depressed, lever 30 will pull through rod 39 upon arm 38 and swing door 4 backwardly and laterally from the approaching car. At 20 the same time motion is transmitted through 15 rod 60, lever 58 and rod 59 to lever 56 and results in the transmission of motion through lever 48 and rod 51 to the arm 52 of door 5. Thus this door will be opened as shown by 25 broken lines in Fig. 1. The car is therefore 20 free to pass through the door opening and before its weight is removed from the depressed rail 10 at one side of the door opening the wheels at the other side of the car will pass onto the other rail 10 at the other 25 side of the door opening and which has already been depressed or pulled downwardly by the actuation of shafts 54 and 45. Consequently the doors will remain open until 30 the car has passed off of the second rail 46 whereupon the spring 57, which had been placed under increased tension by the movement of levers 30 and 56 away from each other, will return all of the parts to their 35 initial or normal positions.

35 It will be apparent that the cushioning means described will absorb all shocks resulting from the sudden application of power by the depression of a rail. Thus injury to the mechanism is not so likely to occur as would 40 be the case should there be no shock absorbing means. Furthermore by providing the particular connections between the operating mechanism and the doors, it becomes possible to make the doors of very light construction 45 because no power is transmitted through them as in many forms of mine doors heretofore devised. As the mechanism can move the doors through ninety degrees or more, 50 said doors can be erected straight across the track. Furthermore the operating mechanism can be extended between the doors and the jambs, thus obviating the necessity of excavating laterally to receive the mechanism. It will be apparent that the spaces 55 left between the doors and the jambs can be closed in any suitable manner as by means of fabric flaps not shown.

55 By providing the operating rail with an 60 upstanding flange supported close to the inner side of the track rail the flange F of a car wheel W resting on the track rail will lap the flange as shown in Fig. 8 and thus prevent the operating rail from shifting laterally away from the track rail during the 65 actuation of the mechanism.

What is claimed is:—

1. Apparatus of the class described including a door frame, oppositely swinging doors mounted therein, a track extending through the frame, upstanding levers on opposite sides of the frame, a depressible operating rail close to one of the rails of the track, cushioning means for transmitting motion from said operating rail to one of the upstanding levers, cushioning means for transmitting motion from the other upstanding lever to one of the doors, means for transmitting motion to the other door from the first named upstanding lever, and a single spring connecting the upstanding levers 70 for holding the doors normally closed and for maintaining the operating rail in raised position.

2. Apparatus of the class described including a door frame, oppositely swinging doors therein normally lapped, a track extending through the door frame, operating rails supported adjacent the respective rails of the track and at opposite sides respectively of the door frame, an operative connection between each rail and one of the doors, upstanding levers at opposite sides of the frame coupled to the operating connections of the respective doors, means operated by the movement of either upstanding lever 85 in one direction for moving the other upstanding lever in the opposite direction, and a spring connecting the upstanding levers 90 for yieldingly holding the doors in closed positions and yieldingly supporting the operating rails.

3. Apparatus of the class described including a door frame, a door mounted to swing therein, a sectional angle rail having upstanding flanges supported close to one of the rails of a track, a movable connection between the sections of the angle rail, yielding means for holding the angle rail elevated and the door closed, means for transmitting motion from the angle rail to the door to open the door, and means for adjusting the angle rail laterally relative to the track rail.

4. Apparatus of the class described including a door frame, a door mounted to swing therein, a track extending through the frame, a depressible operating rail adjacent one of the rails of the track, said operating rail having an upstanding flange, and means for adjusting the operating rail toward the track rail to position the upstanding flange to project between the track rail and the flange of a car wheel supported by said rail.

5. Apparatus of the class described including a door frame, oppositely movable doors hung therein, a track extending through the frame, a depressible operating rail, upstanding levers at opposite sides of the frame, means for transmitting motion thereto from the operating rail, said levers 125

being movable in opposite directions respectively, connections between the levers and the hinge sides of the respective doors, and a single spring connection between the levers **5** for holding the doors normally closed together and the operating rail yieldingly supported.

In testimony that I claim the foregoing as my own, I have hereto affixed my signature in the presence of two witnesses.

WALTER C. CANTERBURY.
